Primary Examiner — Mitchell I. Siegel*(74) Attorney, Agent, or Firm* — Muskin and Farmer LLC**CLAIM**

The ornamental design for a vertical climbing apparatus for playground, as shown and described.

DESCRIPTION

FIG. 1 is an orthographic view of a vertical climbing apparatus for playground showing my new design;

FIG. 2 is a front view of the new design;

FIG. 3 is a right side view of the new design;

FIG. 4 is a rear view of the new design;

FIG. 5 is a left side view of the new design;

FIG. 6 is a top view of the new design; and,

FIG. 7 is a bottom view of the new design.

The broken lines shown are included for the purpose of illustrating unclaimed subject matter and forms no part of the claimed design.

1 Claim, 7 Drawing Sheets
